UNITED STATES PATENT OFFICE.

ADOLPH RUBIN, OF ST. LOUIS, MISSOURI, ASSIGNOR TO SIEBER PRODUCTS MANUFACTURING COMPANY, OF ST. LOUIS, MISSOURI, A CORPORATION OF MISSOURI.

REFRIGERATOR LOCK.

Application filed December 18, 1922. Serial No. 607,724.

To all whom it may concern:

Be it known that I, ADOLPH RUBIN, a citizen of the United States, residing at St. Louis, Missouri, have invented a certain new and useful Improvement in Refrigerator Locks, of which the following is a full, clear, and exact description, such as will enable others skilled in the art to which it appertains to make and use the same.

10 This invention relates to locks of the kind that are used on refrigerators and ice boxes.

The main object of the invention is to provide a refrigerator lock in which the operating handle is combined with the latch of the lock in such a way that the handle will not move when the latch strikes against the stationary keeper on the refrigerator during the operation of closing the refrigerator door, thereby preventing the user's hand from being jarred in such a way that it is apt to slip off of the handle when the latch strikes against the keeper, as so often occurs with locks of the kind that are now generally used on large commercial refrigerators and ice boxes equipped with heavy doors.

Another object is to provide an efficient refrigerator lock of inexpensive construction that is composed of a few rugged parts which are not apt to wear out quickly.

Figure 1 of the drawings is an end elevational view, partly broken away, of a refrigerator lock constructed in accordance with my present invention, designed for use on a left hand refrigerator door, namely, a door in which the hinges are arranged at the left hand edge of the door.

Figure 2 is an end elevational view of a refrigerator lock constructed in accordance with my present invention, designed for use on a right hand door; and

Figure 3 is a rear elevational view of the refrigerator lock shown in Figure 1.

Referring to the drawings, A designates the casing of the lock which preferably consists of a hollow casting provided at one side with a laterally-projecting extension, B designates the latch of the lock, consisting of a relatively long lever pivotally connected at 1 to the extension on the casing A and having its free end projecting outwardly through an opening 2 in one of the side walls of the casing, C designates the keeper that is arranged on the refrigerator

in such a position that it will co-operate 55 with the latch B to retain the refrigerator door in its closed position, and D designates the operating handle of the lock which is pivotally connected by a pivot pin 3 to a pair of forwardly-projecting lugs 4 on the 60 front side of the casing A, it being of course understood that the casing of the lock is secured to the front side of the refrigerator door.

In the conventional refrigerator lock 65 the latch and the operating handle are connected together in such a way that the operating handle will rock or move each time the latch strikes against the keeper during the operation of closing 70 the refrigerator door. This is objectionable, especially in large commercial refrigerators which are equipped with heavy doors, as the operating handle of the lock is used to swing the door into its closed position, and when the operating handle is moved by reason of the latch striking against the keeper, there is a tendency for the handle to jump 75 out of the hand of the person closing the door.

The main object of my invention is to provide a refrigerator lock that does not have this objectionable characteristic, and therefore, I have devised a lock in which the operating handle D and the latch B are connected with each other in such a manner that the latch B is free to move upwardly when it strikes the keeper C without imparting movement to the handle D, thereby producing a lock in which the handle D 80 remains stationary with relation to the door during the operation of closing the door. So far as my broad idea is concerned it is immaterial what means is employed for connecting the latch B with the operating handle D, so long as said means is of such a character that the latch B can be disengaged from the keeper C by operating the handle D preparatory to opening the refrigerator door, and the handle D will remain stationary or will not rock on its pivot 85 when the latch B strikes against the keeper during the operation of closing the door. In the form of my invention herein illustrated the handle D is provided with an angularly-disposed portion 5 that projects into the casing A through an opening in the front side of same, and said angularly-dis-

posed portion 5 is pivotally connected at 6 to a vertically-reciprocating member E whose lower end portion has a sliding connection with the casing A of the lock. The 5 member E extends transversely across the rear side of the latch B, and said member is provided at its lower end with a vertically-disposed, elongated slot 7 that receives a stationary guide pin 8 on the casing 10 A. In order to transmit movement from the member E to the latch B when said member E is moved upwardly by rocking the handle D of the lock forwardly and permit the member E and handle D to remain at rest when the latch strikes against the keeper, the latch B is provided with a shiftable bearing device F that is interposed between the underside of the latch B and a shoulder 9 on the vertically-movable member E, as shown in Figures 1 and 3. Said bearing device F is preferably constructed in the form of a lever pivotally connected at one end by a pintle or pivot pin 10 to depending lugs 11 on the underside of the 25 latch B and provided at its opposite end with a curved bearing portion 12 that lies between the latch B and the shoulder 9 on the vertically-movable member E. A coiled contractile spring G is connected at its upper end to the bearing device F at a point intermediate the ends of said device, and said spring G is connected at its lower end to the casing A preferably by means of a pin 13 on the inside of the casing that 30 projects into an eye on the lower end of the spring G.

When it is desired to disengage the catch B from the keeper C, the handle D is rocked forwardly, thereby moving the member E 40 upwardly and causing the shoulder 9 on said member to co-operate with the curved portion 12 of the bearing device E to move the latch B upwardly out of engagement with the keeper C. As soon as the handle D is 45 released, the spring G will restore the latch B, the vertically-movable member E and handle D to their former positions. Thereafter, when the door of the refrigerator is moved into its closed position, the roller 14 50 of the latch B rides upwardly over the inclined surface 15 on the keeper, and thus rocks the free end of the latch B upwardly. This upward movement of the free end of the latch B has no effect, however, on the 55 handle D or on the latch operating member E connected with the handle, due, of course, to the fact that there is no pivotal connection or positive connection between the latch B and the vertically-movable operating member E. On the contrary, the upward movement of the free end of the latch B merely causes the curved portion 12 on the bearing device F to rock on the shoulder 9 on the vertically-movable member E, or slide over 60 said shoulder without disturbing the posi-

tion of the member E or the handle D. As soon as the roller 14 on the latch passes over the high point of the keeper C, the spring F contracts, and thus restores the latch B and bearing device F to their former positions. It will thus be seen that with a refrigerator lock of the construction above described the handle D is rigid and stationary with relation to the door, when the latch strikes against the keeper, and consequently, 70 there is no danger of the user's hand slipping off the handle, as so often occurs with the conventional refrigerator lock in the operation of closing the door. Moreover, as the lock is composed of only a few parts of rugged design, the lock is inexpensive to manufacture and the parts of same will not wear out quickly, and thus reduce the efficiency of the lock as a means for holding a 75 refrigerator door tightly closed. 80 85

Having thus described my invention, what I claim as new and desire to secure by Letters Patent is:

1. A refrigerator lock, comprising a pivotally mounted latch, a handle, an operating member connected to said handle, and a bearing device interposed between said operating member and latch for moving the latch when the handle is actuated and for permitting the handle to remain at rest when the latch engages its co-operating keeper during the operation of closing the refrigerator door. 90

2. A refrigerator lock, comprising a pivotally mounted latch adapted to co-operate with a keeper to retain the refrigerator door in its closed position, a spring that exerts pressure on said latch in one direction, a handle, an operating member connected to said handle for moving said handle in opposition to said spring, and a bearing device interposed between said operating member and latch that transmits movement to the latch when the handle is actuated and which shifts relatively to said operating member without imparting movement to same when the latch engages the keeper during the operation of closing the door. 100 105 110

3. A refrigerator lock, comprising a pivotally-mounted latch adapted to co-operate with a keeper to retain the refrigerator door in its closed position, a handle, an operating member connected to said handle, and a bearing device pivotally connected to said latch and having a portion interposed between the latch and a shoulder on said operating member. 115 120

4. A refrigerator lock, comprising a pivotally-mounted latch adapted to co-operate with a keeper to retain the refrigerator door in its closed position, a handle, an operating member connected to said handle, a bearing device pivotally connected to said latch and having a portion interposed between the latch and a shoulder on said operating mem- 125 130

ber, and a spring connected to said bearing device for normally holding said latch and handle in a certain position.

5. A refrigerator lock, comprising a casing, a pivotally-mounted latch on said casing, a handle carried by said casing, a reciprocating operating member connected to said

handle and provided with a shoulder, and a spring-pressed bearing device pivotally connected to the latch and having a curved portion that is interposed between the latch and the shoulder on said operating member. ¹⁰

ADOLPH RUBIN.
